UNITED STATES PATENT OFFICE.

CURT SEIDENBERG, OF BEECHER, ILLINOIS.

TOBACCO-PIPE.

1,071,356.

Specification of Letters Patent. Patented Aug. 26, 1913.

Application filed January 15, 1913. Serial No. 742,202.

To all whom it may concern:

Be it known that I, CURT SEIDENBERG, a subject of the Emperor of Germany, residing at Beecher, in the county of Will, State of Illinois, have invented certain new and useful Improvements in Tobacco-Pipes; and I do hereby declare the following to be a full, clear, and exact description of the invention, such as will enable others skilled in the art to which it appertains to make and use the same.

This invention relates to tobacco pipes.

The object of the invention resides in the provision of a tobacco pipe which is so constructed and arranged as to completely consume the entire charge of tobacco placed therein whereby economy in the consumption of tobacco is effected.

Still another object of the invention resides in the provision of a tobacco pipe which may be repeatedly filled with tobacco while same is lighted and the necessity of relighting the pipe during the filling obviated.

A still further object of the invention resides in the provision of a tobacco pipe in which the removal of ashes may be effected with facility and which also includes means for preventing the tobacco from spilling and sparks or ashes from being blown from the bowl when the pipe is in use.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a longitudinal section through the pipe constructed in accordance with the invention; Fig. 2, a longitudinal section of the bowl of the pipe detached and showing the grate and its holder operated to position to permit free rotation of the grate to effect disengagement of the ashes in the pipe; Fig. 3, a section on the line 3—3 of Fig. 1, with the stem of the bowl rotated to position to permit disengagement of same from the smoke reservoir, and Fig. 4, a retail perspective view of the grate.

Referring to the drawings 10 indicates

the mouth piece of the pipe and A the smoke reservoir. This reservoir A is of substantial cup shape and has its mouth of such diameter as to snugly receive one end of the mouth piece 10 in the usual and well known manner. The reservoir A has an opening 11 formed in the wall thereof adjacent the mouth of said reservoir. Projecting from the wall of said reservoir slightly above the opening 11 is a bowl securing finger 12, 60 the free end of which is directed longitudinally of the reservoir toward the bottom of the latter. The reservoir A is provided with a partition 13 which forms a smoke passage 14, said passage connecting at its 70 lower end with the interior of said reservoir. The bowl of the pipe which is indicated at B is shown as comprising a tubular member, the upper end of which is adapted to be closed by the cap 15 hinged to the 75 bowl, making it airtight at the upper end. The lower end of the bowl B is reduced as at 17 and the outer side of this reduced portion is exteriorly threaded as at 18.

Engaged with the threads 18 is a tubular 80 member 19 which is provided at its outer end with an inwardly directed flange 20 supporting the grate 21. Formed integral with this grate on the inner side of the latter are projections 22 for a purpose that will 85 presently appear. The outer end of the tubular member 19 is closed by a cover 20' the side wall of which is provided with air openings 21'. The bowl B is provided with a laterally directed tubular stem 23 which 90 is inserted through the opening 11 of the smoke reservoir. The passage of the stem 23 extends diagonal of said stem so that when the latter is inserted in the opening 11 in proper assembled relation said passage 95 will communicate with the upper end of the passage 14 of the smoke reservoir. Formed on the stem 23 is a lateral projection 24 which is adapted to coöperate with the finger 12 to secure the bowl against disengagement from the smoke reservoir. In applying the bowl to the reservoir the former is positioned out of the plane of the latter and the stem 23 inserted in the opening 11 until the projection 24 engages the reservoir. The bowl is then rotated into the plane of the reservoir when the projection 24 will pass behind the outer end of the finger 12 and thus secure the bowl against disengagement from the reservoir. 100 105 110

In the use of the pipe the tobacco is supplied through the upper end of the bowl and the cap 15 closed. The tobacco is then lighted at the bottom of the bowl and 5 smoking proceeded with. It will be noted that during the use the smoke will pass through the passage of the stem 23, thence through the passage 14, through the main portion of the reservoir A in an upward direction and then through the mouth piece 10. During this prolonged movement of the smoke from the bowl to the mouth of the user same will become thoroughly cooled, while all moisture will settle in the bottom 10 of the reservoir A. If it is desired to remove the ashes from the bowl A the member 19 is screwed on the lower end of the bowl B until the threads of the member 19 are disengaged from the threads 18. The member 19 and the grate 21 can then be freely rotated so that the movement of the projections 22 will loosen and free all ashes in the pipe. To completely clean the bowl of the pipe it is only necessary to rotate the member 19 to the left and thereby effect the 25

disengagement of both the member 19 and the grate 21.

What I claim is:—

In a tobacco pipe, the combination of a tubular bowl having a hinged cover for closing its upper end, said bowl terminating at its lower end in an exteriorly reduced portion provided with threads at its outer side, an interiorly threaded tubular member engaged with the threads of the bowl, the threads of said tubular member being adapted to pass out of engagement with the threads of the bowl when said member is screwed on the bowl a predetermined distance, a grate supported by said tubular member, projections on the inner side of said grate, a mouth piece, and draft connections between the mouth piece and the bowl.

In testimony whereof, I affix my signature, in the presence of two witnesses,

CURT SEIDENBERG.
